INVENTOR
Benjamin Bacon

United States Patent Office.

BENJAMIN R. BACON, OF PHILADELPHIA, PENNSYLVANIA.

Letters Patent No. 2,818, dated November 5, 1867.

DESIGN FOR A BURIAL CASKET.

The Schedule referred to in these Letters Patent and making part of the same.

ALL WHOM IT MAY CONCERN:

Be it known that I, BENJAMIN R. BACON, of the city and county of Philadelphia, and State of Pennsylvania, have invented a new and useful Design for Burial Caskets; and I do hereby declare the following to be clear and exact description of the nature thereof, sufficient to enable others skilled in the art to which it pertains to fully understand and use the same, reference being had to the accompanying drawings, making part of this specification, in which—

Figure 1 is a plan or top view of a burial casket constructed according to my design.

Figure 2 is a side elevation thereof.

Similar letters of reference indicate corresponding parts in the two figures.

My invention is a new and useful design for burial caskets, being beautiful, simple, and ornamental, and combining a strong and durable receptacle, with but little more expense than the unsightly and repulsive coffins now in use. In the drawings—

A represents the body of the coffin, and A' the cover or lid, both having their sides *a* parallel, and running broken to the point *b*. The head and foot or end pieces B C are curved outwardly, as shown at *c*, and form arcs or segments, *d e*, of a circle, having the same curvature and length. The point *b* of the sides *a*, and the points *d* and *e* of the head and foot pieces, are united by arcs or segments *D*, being about forty degrees, and forming "rounded cut-off" corners *b B d* and *b B e*, whose curvatures are inwardly. The lid or cover A' is of a raised or ridged form, constructed with mouldings *E*, which are placed or applied on the lid at points between the middle and edges. The members of the moulding correspond in the direction in which they run with the sides *a* and end pieces B C, that is, the mouldings *a'* run parallel with the sides *a*. The top and bottom mouldings *c'* correspond with the arc *c* of the head and foot-pieces B C. The top and bottom mouldings *c'* are united to the side mouldings by the arc or segment mouldings *D'*, which correspond with the segments which form the cut-off corners. It will be perceived that the end *c* and moulding *c'* are concentric, as are the mouldings *D'* and segment or cut-off corners *D*. Suitable beads *f* may be placed around the edges of the lid and the sides of the body A. Handles and pins or studs also may be added thereto, if desired.

A casket constructed according to the above design is durable, neat, and ornamental.

Having thus described my invention, what I claim as new, and desire to secure by Letters Patent, is—

The design for burial caskets, substantially as represented and described.

To the above I have signed my name this eighth day of October, 1867.
